Gordon W. Lloyd

UNITED STATES PATENT OFFICE.

GORDON W. LLOYD, OF DETROIT, MICHIGAN.

IMPROVED MODE OF CONSTRUCTING AND ARRANGING FOOT-LIGHTS FOR THEATERS.

Specification forming part of Letters Patent No. 35,696, dated June 24, 1862.

To all whom it may concern:

Be it known that J. GORDON W. LLOYD, of Detroit, in the county of Wayne, in the State of Michigan, have invented a new and Improved Mode of Constructing and Arranging Foot-Lights on the Stages of Theaters and other Buildings of Like Nature; and I do hereby declare that the following is a full and exact description thereof, reference being had to the accompanying drawing, and to the letters of reference marked thereon.

The nature of my invention consists in placing the lights A in a trough sunk in the front of the stage below the ordinary floor-level, as shown, and employing a continuous reflector, B, to reflect the light at such an angle and direction as may be desired, the back of the reflector forming a screen from the audience; the arrangement admitting also of the reflecting onto the stage lights of any color by the substitution or insertion from below, or other-

wise, of suitable reflecting-surfices; also, in providing a covering of fine metal wire-cloth, c, above the burners to prevent contact with the dresses of performers, and hinged to admit of access for any purpose.

What I claim as my invention, and desire to secure by Letters Patent, is—

1. The position and mode of arrangement of the lights with the continuous reflector, as distinguished from the mode now ordinarily in use.
2. The power of throwing colored lights on the stage, as above described.
3. By means of the guard formed by the sunken trough and the wire-cloth covering, greatly increased safety to performers.

GORDON W. LLOYD.
